UNITED STATES PATENT OFFICE.

HIRAM McNICHOLAS, OF CONNELL, WASHINGTON.

GRINDING-TOOL

1,370,141.

Specification of Letters Patent.

Patented Mar. 1, 1921.

Application filed January 15, 1920. Serial No. 351,552.

To all whom it may concern:

Be it known that I, HIRAM McNICHOLAS, a citizen of the United States, residing at Connell, in the county of Franklin and 5 State of Washington, have invented certain new and useful Improvements in Grinding-Tools, of which the following is a specification.

My present invention relates to an improved grinding tool for grinding curved surfaces, and involves a manually operated tool for this purpose especially adapted for grinding and truing journal bearings of shafts. The subject matter of the invention 10 is especially useful in grinding and truing the journal bearings of crank shafts of internal combustion engines, wherein the shafts are difficult of access for grinding and usually are removed entirely from the 15 engine for the purpose. By the utilization of my invention I am enabled to grind the journal bearings of the crank shaft without the necessity for removing the shaft from its engine, by first disconnecting the 20 connecting-rod from the journal bearing, and then applying to the journal bearing the oscillatable or rotary grinding tool, and the bearing is then ground and trued by manipulation of the tool while on the bearing. 25

To attain the above ends and achieve the required results I utilize a sectional tool head having a handle for manual operation with an oscillatable motion on the bearing, 30 and the invention consists essentially in combining with the tool head in novel formation, grinding or abrasive members for frictional contact with the bearing, that involve certain novel features and combinations and arrangements of parts as will be 35 hereinafter more fully described and claimed.

In the accompanying drawings I have 40 illustrated one complete example of the physical embodiment of my invention in which the parts are combined and arranged according to the best mode I have so far devised for the practical application of the principles of my invention.

Figure 1 is a side view of the tool, showing one section in vertically cut away position, and Fig. 2 is the other section or member of the tool head in full side elevation.

For convenience of illustration and description I shall confine the invention herein described to use with a crank shaft 1 and

its bearings or journals 2, but it will be understood of course that the tool is adapted with equal facility for grinding and truing other cylindrical curved surfaces. As is 60 well known in the art the journal bearings 2 of the shaft 1 in internal combustion engines frequently become worn to an elliptical form in cross section, and the tool is specially adapted for truing and grinding these 65 deformed bearings, being formed with a tool-head comprising the separable sections 3 and 4 that may be clamped around the bearing or journal to be trued while the shaft is in normal position, but after the 70 connecting rod has been detached from the shaft.

The two tool sections are semicircular and each fashioned with a pair of lateral integral lugs 5 and 6, the opposed lugs being 75 arranged parallel and alined to receive the clamp bolts 7, and the lugs are spaced apart by the spacing bolt-nuts 8, 8, threaded on the bolts and jammed against the adjoining faces of the lugs as shown in Fig. 1, while 80 the protruding threaded ends of the bolts are provided with butterfly nuts 9 for clamping and securely holding the bolts and lugs in rigid relation.

In placing the tool head in position for 85 grinding, it will readily be apparent that the separated sections are placed about the journal, having previously been adjusted as to the spacing nuts, and the butterfly nuts are turned home to clamp the tool sections 90 in rigid relation in order that the head may be oscillated on the journal. For the required oscillatory movement of the head I utilize a selected one of the several bosses 10, a pair of which is provided on each section, and the bosses form integral sockets for the insertion of the threaded end of a handle bar or rod 11 of usual shape and suitable length to be grasped by the hand and threaded into the socket and form the 100 handle for manipulating the tool head in oscillatory movement on the journal.

Each section of the tool head is fashioned with a dove-tail socket 12 having a lateral opening as indicated at the lower section 105 in Fig. 1 and having an inner opening likewise illustrated in Fig. 1, to accommodate the abrasive blocks 13 in their housings or casings 14. The blocks are of suitable abrasive material as emery or stone, and are 110 formed as circular segments or portions of a ring to be retained in the housings or

casings 14 preferably of metal and fashioned with a curved base 14', end flanges 14^a, and a side flange 14^b, thus permitting insertion of the segmental block or stone, 5 laterally in the housing, and the housing may in turn be inserted, laterally in its socket 12, as will be readily understood. At one of its ends each of the housings is fashioned with a transverse rib 15, in- 10 tegral with a flange 14^a, and the rib is seated in a complementary groove 16 in the lug 16' of the tool section with a freedom of movement to enable the housing to swing to a limited degree on the rib and groove as a 15 hinge or pivot. The lug in each section is centrally located and forms the end wall of the complementary sockets in the sections and the grooves are formed, near the inner periphery of the sections and disposed in 20 opposed relation at the opposite sides of the center lug as shown in Fig. 1. It will be noted that the housings for the abrasive blocks are smaller than their sockets, to permit the interposition of cushion members 17, 25 of rubber or other resilient material, between the walls of the sockets and the housing, these members or casings being shaped to engage between the free end of the housing and the end wall of a socket and be- 30 tween the curved outer periphery of the housing and complementary wall of the socket.

By means of the complementary formation of the socket, metal casing, block, and re- 35 silient cushion, it will be apparent, the block is retained in its socket, but, as before stated, the block is permitted to have a pivoted movement on the rib and groove in order that its opposite end may be forced inward 40 toward the center of axis of the tool head. For this purpose a set screw 18 is provided for each block, threaded through a socket or aperture 19 in the tool section, and bearing on the metal casing of the block. When 45 the adjusting screw 18 is turned in the proper direction, the free end of the block and its casing are forced inwardly as indicated in Fig. 1, in order that, in addition to the approximate adjustment provided for 50 between the two tool-head sections, a closer adjustment may be had for frictional engagement with the journal bearing by the abrasive members.

The tool is oscillated by alternately push- 55 ing and pulling on the handle 11 and the head is oscillated transversely of the shaft

and its journal, and the successive grinding movements of the adjusted abrasive or grinding blocks in frictional engagement with the journal will grind down the periphery of the journal and true its surface. At the start of the grinding operation, the irregular or protruding portions of the journal bearing, as they are encountered by the resiliently backed grinding members, will 65 cause these members, at their free ends, to swing outwardly, slightly of course, on their pivots or hinges, but the frictional contact is maintained in order that the protrusions may be rubbed down, and as they are rubbed 70 down, the set screws 18 may be gradually turned to force in the grinding blocks to compensate for wear, until the journal is trued. It is desirable that the head be adjusted from time to time on the journal to 75 bring different blocks in contact with other surfaces of the journal, and this may be done by shifting the lever handle from one to another of the selected sockets provided therefor, and the oscillations of the head are 80 continued until the desired result is attained.

In this manner the tool may be applied successively to the journals of the crank shaft, while the latter is still *in situ* and the grinding may be accomplished with fa- 85 cility and despatch.

What I claim is—

1. A separable, sectional tool head having a handle and means for securing the sections about a journal, each section formed with 90 lateral dove-tail sockets having an end groove, a complementary casing in each socket fashioned with an end rib in a groove to form a hinged joint, set screws for said casings, and abrasive members carried in 95 said casings.

2. The combination with a tool head having a lateral dove-tail socket, of a metal casing having a hinged connection with the wall of said socket, an abrasive member in the cas- 100 ing, and means for adjusting said casing on its hinged connection.

3. The combination with a tool head hav- 105 ing a lateral dovetail socket, of a metal casing having a pivotal rib seated in a groove in one end wall of the socket, a resilient cushion member between the casing and two walls of the socket, an abrasive member in said casing, and a set screw in the tool head engag- ing the casing, for the purpose described. 110

In testimony whereof I affix my signature.
HIRAM McNICHOLAS.
